UNITED STATES PATENT OFFICE.

HEINRICH WISCHHUSEN AND ALEXANDER HEPKE, OF BERLIN, GERMANY.

PUSH-BUTTON SWITCH.

1,061,578.

Specification of Letters Patent. Patented May 13, 1913.

Application filed March 25, 1912. Serial No. 686,199.

To all whom it may concern:

Be it known that we, HEINRICH WISCHHUSEN and ALEXANDER HEPKE, citizens of the Empire of Germany, and residing at Berlin, Germany, have invented certain new and useful Improvements in Push-Button Switches, of which the following is a specification.

Our invention relates to press-button switches and a primary object is to provide a simple switch of this type.

In press-button switches known heretofore comprising rotating contact-pieces two members have been provided for returning the press-button into its initial position and for giving the rotatory movement to the movable contact-pieces. According to our invention we employ for these two purposes only one single spiral spring which is subjected both to compressive and to torsional strain.

One illustrative embodiment of our invention is represented by way of example in vertical section in the accompanying drawing.

Referring to the drawing, the central hole in the cover *e* of insulating material is provided with a spiral groove *d* in which is guided the upper, radially bent end *b* of the spiral spring *a*. The lower radially bent end *c* of the spiral spring *a* bears against one of the ratchet teeth on the crown wheel *h* fast on the switch-drum *i*. This drum is fast on the axle *s* and carries the electrically conducting contact-arms *m* and *n* which in the "on" position connect together the two connection-contacts *o* and *p* for the wires *q* and *r*, and thus close the circuit. The axle *s* is journaled in a recess in the base *f* and is guided at its upper end in a bore in the press-button *g*, which is able to move up and down in the central hole in the cover. The upward motion of the press-button *g* is limited by a stop not shown in the drawing.

Any suitable known device may be used for arresting the drum *i* in the "on" and "off" positions. In the illustrative embodiment a square block *k* is fast on the lower end of the axle, and is located between the two flat springs *l*. When the axle *s* carrying the drum *i* is rotated, the square block *k* is driven forward by the action of the springs *l* as soon as it has moved more than 45°, and after rotating 90° from its normal position is arrested between the springs *l*. Now when the press-button *g* is depressed,

the pressure is transmitted to the spiral spring *a* which is compressed in the axial direction. When this spring is depressed its upper radially bent end *b* which is guided in the groove *d* is simultaneously driven circumferentially, the result being that the spring is subjected to torsional strain. The torsion is increased by the continued downward motion of the press-button *d*, until the spring at last overcomes both the friction at the contact-pieces *m*, *n* and the tension of the springs *l*, and the drum *i* flies over into the next stopping position. The torsion of the spring *a* is hereby partly relieved. The remaining torsion apart from the initial torsion which is always present, is used for placing the lower end *c* of the spring behind the next ratchet tooth to the rear on the crown wheel. The press-button *g* is simultaneously forced back by the axial pressure of the spiral spring *d*.

We claim:

1. In a push button switch the combination of a base plate, a cover provided with an inner spiral groove, an axle journaled in said base plate, a drum secured to said axle, a push button movable down and up along said axle, a spiral spring arranged about the axle and having one end adapted to rotate said drum and the other guided in said spiral groove when said spring is compressed by the push button.

2. In a press-button switch, the combination of a base-plate, a cover having a central hole mounted thereon, said hole having a spiral groove, an axle journaled in the base and extending into said hole, a drum fast on the axle under the cover, a press-button movable down and up in said hole, a spiral spring arranged about the axle in said hole and having one end adapted to rotate said drum, the other end of said spring being guided in said groove.

3. In a press-button switch, the combination of a base-plate, a cover having a central hole mounted thereon, said hole having a spiral groove, an axle journaled in the base and extending into said hole, a drum fast on the axle under the cover, a crown wheel rigidly connected with the drum, a press-button movable down and up in said hole, a spiral spring arranged about the axle in said hole and having one end normally resting behind one tooth of the crown wheel, the other end of said spring being guided in said groove.

4. In a press-button switch, the combina-

tion of a base-plate, a cover having a central hole mounted thereon, said hole having a spiral groove, an axle journaled in the base and extending into said hole, a drum fast on the axle under the cover, a crown wheel having four ratchet teeth rigidly connected with the drum, a press-button movable down and up in said hole, a spiral spring arranged about the axle in said hole and having one end normally resting behind one tooth of the crown wheel, the other end of said spring

being guided in said groove, a square block fast on the axle, and two leaf springs normally bearing against opposite faces of the block.

In testimony whereof, we affix our signatures in the presence of two witnesses.

HEINRICH WISCHHUSEN.
ALEXANDER HEPKE.
